UNITED STATES PATENT OFFICE.

THOMAS V. COONY, OF ALBUQUERQUE, TERRITORY OF NEW MEXICO.

VALVE.

SPECIFICATION forming part of Letters Patent No. 557,975, dated April 7, 1896.

Application filed October 15, 1894. Serial No. 525,904. (No model.)

To all whom it may concern:

Be it known that I, THOMAS VINCENT COONY, of Albuquerque, in the county of Bernalillo and Territory of New Mexico, have invented 5 a new and Improved Valve, of which the following is a full, clear, and exact description.

The invention relates to valves controlled by a float and controlling the supply for water-tanks and other devices; and its object is to 10 provide a new and improved valve which is comparatively simple and durable in construction and arranged to prevent leakage and be perfectly noiseless when opening and closing.

15 The invention consists of certain parts and details and combinations of the same, as will be fully described hereinafter, and then pointed out in the claims.

Reference is to be had to the accompanying 20 drawings, forming a part of this specification, in which similar letters of reference indicate corresponding parts in all the figures.

Figure 1 is a side elevation of the improvement as applied in a tank shown in section. 25 Fig. 2 is an enlarged sectional side elevation of the improvement on the line 2 2 of Fig. 3, and Fig. 3 is a transverse section of the same on the line 3 3 of Fig. 2.

The improved float-valve is provided with 30 a valve-body A, formed at its lower end with a shank B, adapted to pass through the bottom of the tank C and adapted to be engaged by a nut B' to securely screw the valve-body in position within the tank, as plainly indicated in Fig. 1. The lower outer end of the 35 shank B is connected in the usual manner with the supply-pipe D, connected with a suitable source of water supply, usually with the service-pipe of the building.

40 In the valve-body A, at the upper end of the bore of the shank B, is formed a valve-seat A', adapted to be engaged by a leather-covered face E' of the valve E, mounted to slide in the opening A², formed in the valve-body A, as is 45 plainly illustrated in the drawings. In the valve E is arranged a longitudinally-extending opening E², in which extends the end F' of the float-lever F, fulcrumed at F² on the valve-body A, the outer end of the said lever 50 carrying the float F³, adapted to be raised and lowered by the rising and receding water in the tank C.

The end F' of the lever F extends through an opening A³ in the side of the valve-body A, and the latter is also provided with outlet-apertures A⁴, leading to the opening A² at or near the lower end thereof, so that when the valve E is raised off the seat A' the water from the supply-pipe D can pass through the shank B and seat A' into the opening A² and from 60 the latter through the openings A⁴ into the tank C to fill the same.

The upper end of the valve E is somewhat enlarged to form a piston E³, mounted to slide in the cylinder A⁵, formed in the upper end 65 of the valve-body A, and this piston is formed with a central bore E⁴, opening into the opening E² at its lower end and formed at its upper end with a valve-seat E⁵, adapted to be engaged by a drip-valve G, having its stem G' 70 passing through the bore E⁴ to project into the opening E² and in alinement with the end F' of the lever F, so that the latter is adapted to engage with its end F' the said stem G' to raise the valve G off the seat E⁵ at the time 75 the float F³ is descending.

The upper end of the cylinder A⁵ is connected by a small port a, leading into a channel b, formed on the side of the valve-body A and leading into the shank B below the valve-seat A'. (See Fig. 2.)

The operation is as follows: When the tank is filled with water, as illustrated in Fig. 1, then the float F³ is in an uppermost position and the end F' of the lever F holds the valve 85 E firmly onto the seat A', so that the supply of water to the tank is shut off. When the tank C is emptied, then the float F³ moves downward and causes a swinging of the float-lever F, whereby the end F' first moves in 90 contact with the stem G' to raise the drip-valve G off its seat, whereby communication is effected between the upper end of the cylinder A⁵, containing water under pressure, and the opening E², so that the pressure in the 95 cylinder A⁵ is relieved and the valve is free to rise off its seat A' to admit water to the tank C. When the valve moves upward, the piston E³ closes the port a, shutting off the pressure from the cylinder A⁵. As the float 100 now rises and the water accumulates in the tank C it causes the end F' to move downward and move the valve E in a like direction, and finally onto its valve-seat A' to shut off

the supply. In swinging downward the end F' moves away from the lower end of the stem G' to permit the drip-valve G to again seat itself on the seat E³, so that the water under 5 pressure in the upper end of the cylinder A⁵ acts on the piston E³ to finally seat the valve E and securely hold the same to its seat.

It will be seen that the piston E³ in its downward movement, by the action of the float-lever F, uncovers the port a just previous to 10 the final seating of the valve E, so that the lever F moves the valve in a downward direction unaided by water-pressure from above until the valve is nearly seated, after which 15 the pressure from the supply in the upper end of the cylinder A⁵ acts on the piston E³ to quickly seat the valve.

As the chamber or cylinder in the upper 20 part of the valve-casing is enlarged and as the upper or piston portion of the valve is of greater diameter than the lower portion, it will readily be seen that when the port a is 25 opened the pressure upon the upper surface of the valve will exceed the pressure upon the lower surface and the valve will be quickly forced to its seat. When the valve is thus seated, the excess of pressure upon its upper 30 surface will hold the valve firmly to its seat and it will not be affected by any fluttering of the water in the tank which might cause the float to bob.

It will be seen that by the construction described the valve is rendered perfectly noiseless in opening and closing, and as the outlets for the water are submerged in the water 35 contained in the tank C the usual noise so frequently observed in supply-valves as previously constructed is entirely obviated.

Having thus fully described my invention, 40 I claim as new and desire to secure by Letters Patent—

1. A supply-valve, comprising a valve body or casing formed with a valve-seat and a cylinder, a valve proper adapted to be seated on 45 the said valve-seat and provided with a piston portion engaging the said cylinder, a float-lever extending into an opening in the valve proper and adapted to engage directly with the upper and lower walls of the said opening, a drip-valve held on the valve proper and having a stem extending into the path of the 50 float-lever, the cylinder portion of the valve being provided with a port adapted to be

opened and closed by the piston portion of the valve, the said port connecting the upper 55 end of the cylinder with a channel leading to the supply, the free end of the said float-lever fitting loosely in the opening in the valve proper, whereby when the pressure is removed from above the valve, the said valve 60 will have free upward movement, as and for the purpose set forth.

2. A supply-valve, comprising a valve body or casing formed with an upwardly-projecting valve-seat and having a recess at the 65 sides of the valve-seat communicating with outlet-openings extending through the sides of the casing, the said valve body or casing having an enlarged chamber or cylinder at its upper end, and communicating at its 70 lower end with the water-supply, a valve proper adapted to be seated on the said valve-seat and provided with an enlarged portion or piston fitted to move in the said enlarged chamber or cylinder, the said valve proper 75 being formed with an opening, a float-lever extending into the said opening in the valve and adapted to engage directly with the upper and lower walls of the said opening to move the said valve in opposite directions, 80 the end of the float-lever fitting loosely in the said opening, whereby the said valve has movement independent of the movement of the lever, a drip-valve fitting a seat on the said piston portion of the valve and having 85 a stem extending through a bore in the piston and projecting into the opening in the valve in line with the end of the float-lever, the cylinder or enlarged portion of the casing being provided with a port adapted to be 90 opened and closed by the piston portion of the valve and connecting the upper end of the cylinder with a channel leading to the supply below the valve-seat, whereby when the said port is closed and the pressure is removed from above the valve, the valve will 95 be forced open to its full extent, and when the said port is opened, the pressure above the valve will exceed the pressure below the valve and the valve will be quickly forced to its 100 seat and firmly held thereon, as and for the purpose set forth.

THOMAS V. COONY.
